(57) **CLAIM**

The ornamental design for a machining sample model of machine tools, as shown and described.

DESCRIPTION

FIG. 1 is a front perspective view of a machining sample model of machine tools showing our new design;

FIG. 2 is a rear perspective view thereof;

FIG. 3 is a top plan view thereof;

FIG. 4 is a rear view thereof;

FIG. 5 is a front view thereof;

FIG. 6 is a right side view thereof; and,

FIG. 7 is a left side view thereof.

The broken lines represent portions of the machining sample model of machine tools which form no part of the claimed design.
